CLAIM

The ornamental design for a telephone handset, as shown and described.

DESCRIPTION

FIG. 1 is a bottom plan view of a telephone handset showing my new design;

FIG. 2 is an elevational view of one side, the view of the side opposite being a mirror image thereof;

FIG. 3 is a top plan view thereof;

FIG. 4 is a rear elevational view taken in the direction of the arrow 4 in FIG. 2; and

FIG. 5 is a front elevational view taken in the direction of the arrow 5 in FIG. 2.
